UNITED STATES PATENT OFFICE

HERMANN NONNAST, OF CHICAGO, ILLINOIS

DESIGN FOR A COMBINED CABINET AND TABLE

Application filed May 19, 1932. Serial No. 43,849. Term of patent 7 years.

To all whom it may concern:

Be it known that I, HERMANN NONNAST, a citizen of the United States of America, and a resident of the city of Chicago, in the county of Cook and State of Illinois, have invented a new, original, and ornamental Design for a Combined Cabinet and Table, of which the following is a specification, reference being had to the accompanying drawing, forming part thereof.

In the drawing:

Fig. 1 is a front elevational view of a combined cabinet and table, showing my design.

Fig. 2 is a side elevational view thereof, showing the table in the contracted position.

Fig. 3 is a side elevational view thereof, showing the table in the extended position.

I claim:

The ornamental design for a combined cabinet and table, as shown and described.

Signed at Chicago, in the county of Cook and State of Illinois, this 17th day of May, 1932.

HERMANN NONNAST.
